DESCRIPTION

FOREIGN PATENT DOCUMENTS

FIG. 1 is a front elevational view of the retainer for a connected electrical extension cord showing my new design;

0818717 7/1969 Canada 439/369

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is an isometric view thereof showing the retainer in use. The broken line showing of the extension cord is included for the purpose of illustrating environmental elements only and forms no part of the claimed design.
